(57) **CLAIM**

The ornamental design for a hearing device, as shown and described.

DESCRIPTION

FIG. 1 is a first perspective view of an embodiment of a hearing device, showing the new design.

FIG. 2 is a second perspective view of the hearing device of FIG. 1.

FIG. 3 is a front view of the hearing device of FIG. 1.

FIG. 4 is a back view of the hearing device of FIG. 1.

FIG. 5 is a top view of the hearing device of FIG. 1.

FIG. 6 is a bottom view of the hearing device of FIG. 1.

FIG. 7 is a first side view of the hearing device of FIG. 1.

FIG. 8 is a second side view of the hearing device of FIG. 1.

FIG. 9 is a detailed perspective view of a first portion of the hearing device of FIG. 1.

FIG. 10 is a detailed perspective view of a second portion of the hearing device of FIG. 1.

FIG. 11 is a cross sectional view of the first portion of the hearing device of FIG. 9.

FIG. 12 is a cross sectional view of the second portion of the hearing device of FIG. 10.

FIG. 13 is a first perspective view of another embodiment of a hearing device, showing the new design.

FIG. 14 is a second perspective view of the hearing device of FIG. 13.

FIG. 15 is a front view of the hearing device of FIG. 13.

FIG. 16 is a back view of the hearing device of FIG. 13.

FIG. 17 is a top view of the hearing device of FIG. 13.

FIG. 18 is a bottom view of the hearing device of FIG. 13.

FIG. 19 is a first side view of the hearing device of FIG. 13.

FIG. 20 is a second side view of the hearing device of FIG. 13.

FIG. 21 is a detailed perspective view of a first portion of the hearing device of FIG. 13.

FIG. 22 is a detailed perspective view of a second portion of the hearing device of FIG. 13.

FIG. 23 is a cross sectional view of the first portion of the hearing device of FIG. 21; and,

(Continued)

FIG. 24 is a cross sectional view of the second portion of the hearing device of FIG. 22. The broken lines depict portions of the hearing device that form no part of the claimed design.

1 Claim, 20 Drawing Sheets
